UNITED STATES PATENT OFFICE.

GEORGE C. MURRAY, OF CHICAGO, ILLINOIS, ASSIGNOR TO KEYOKE RAILWAY EQUIPMENT COMPANY, A CORPORATION OF DELAWARE.

UNCOUPLING MECHANISM.

1,098,392.

Specification of Letters Patent.

Patented June 2, 1914.

Application filed February 16, 1914. Serial No. 819,626.

To all whom it may concern:

Be it known that I, GEORGE C. MURRAY, a citizen of the United States, residing at Chicago, in the county of Cook and State of Illinois, have invented certain new and useful Improvements in Uncoupling Mechanism, of which the following is a specification.

This invention relates to improvements in uncoupling mechanisms, and has for its object to provide a new and improved form of device which may be cheaply and readily manufactured, and which may be easily attached to or detached from a car.

Still another object of my invention is to provide a mechanism of the class described comprising but two operating parts and arranged to be mounted so that the operator may pull the operating lever toward him and the side of the car to uncouple the same, thereby obviating the danger of standing between the cars to uncouple the same.

Still another object is to provide a mechanism of the class described which may be attached to the end sill of a car leaving the hand hold carried thereby unrestricted so as to comply with Interstate Commerce regulations and the like.

These and other objects will be set forth and shown in the following specification and accompanying drawing, in which;

Figure 1 is a perspective of my mechanism showing the same applied to the end sill of a car; Fig. 2 is a plan view of the same; Fig. 3 is a detail section through one of the pivotal supports.

Like numerals refer to like elements throughout the drawings, in which; 10 designates generally a car having an end sill 11, and coupler 12 provided with the usual 20 coupler pin 13. The latter has the loop or eye 13^a for engagement by the coupler mechanism which comprises in my invention, what I term the uncoupler rod 15 and operating lever 16. The former is provided with 30 the eye or loop 15^a loosely mounted on the pivotal support 17. On the coupler side of this pivotal support 17 the coupler rod is bent outwardly, as indicated by numeral 15^b, see Fig. 2. The rod 15 is further provided 40 with the portion 15^c angularly bent with respect to portion 15^b and fitting loosely through the loop 13^a of the coupler 13. The rod 15 is further provided with the portion 15^d on the opposite side of the mounting 17, 50 this portion terminating in the eye or loop

15^e and normally diverging slightly from the end of the car, as shown in Fig. 2. The operating lever is formed with the angularly disposed arms 16^a, 16^b, the latter comprising an engaging handle. In the embodiment shown, the rod 16 is bent to form the said arms and is provided with the enlarged loop or eye 16^c at the intersection of these arms, this loop passing through the eye 15^e of rod 15, the handle arm 16^b being located outwardly of arm 16^a to insure sufficient clearance between the same and the end sill. At its extremity, the arm 16^a is looped or apertured, as indicated by numeral 16^d and is loosely mounted upon a pivotal mounting 18, similar to 17. In its normal coupling position, as shown in Fig. 1, the arm 16^a extends downwardly slightly from the loop 16^c.

The operation of the device is as follows:—When it is desired to uncouple the cars or raise the coupler pin 13, arm 16^b is pulled toward the adjacent side of the car 10, the loop 16^c thereby being rotated in an arc about pivotal mounting 18. At the same time the portion 15^d of coupler 15 is pulled downwardly and portion 15^e thereof is raised, operating to raise the coupler pin 13 to uncoupling or lock said position. This pivotal movement of the rod 15 is made possible by the elongated loop 16^c and the loose engagement therewith of loop 15^e, and by inclining the arm 16^a upwardly from mounting 18, it will be apparent that loop 16^c and loop 15^e move both upwardly and downwardly of a horizontal line through the mounting 18, so that the lateral relative movement of operating lever 16 and uncoupling rod 15 is reduced to a minimum. The loose mounting of rod 15 upon the pivotal support 17, and the similar mounting of rod 16 upon mounting 18, together with the play between the looped portions 15^e—16^c, enables the required motion of the coupler 12 in all directions to take place without cramping or bending the coupler mechanism. Similarly by the outward divergence of the arms 15^a and 16^a from the end sill, inward movement of the same when caused by the outward movement of the coupler, will be permitted; also the arrangement and construction of my mechanism permits the placing of the hand hold 19 in its most advantageous position without hampering the use thereof.

In Fig. 3 I have shown in detail the construction of the pivotal mounting 17, in which I utilize a sleeve or thimble 17^a having the circular shoulder 17^b therearound. 5 This sleeve or thimble is provided with the socket 17^c in its base, preferably non-circular to form a seat for the similarly shaped head 17^d of bolt 17^e which extends through the thimble 17^a and projects outwardly 10 thereof. A washer or collar 17^f is fitted on the reduced portion of thimble 17^a and rests against the shoulder 17^b. Similarly a washer or collar 17^g rests against the outer end of the thimble 17^a and is normally secured in place by the nut 17^h threaded on the end of bolt 17^e, the same serving to hold the collar 17^g in place and also serving to securely clamp the head of the bolt 17^d securely 15 in its socket 17^c. The looped portion 15^a 20 of the rod 15 fits loosely over the reduced portion of thimble 17^a between the collars 17^f—17^g and it is apparent that the same may be readily detached therefrom by removing the nut 17^h and collar 17^g. Pivotal 25 mounting 18 is similar in construction and arrangement and need not be described in detail.

It will be apparent that my invention is susceptible of many modifications and improvements, and I do not wish to be restricted to the same beyond the scope of the appended claim. 30

What I claim is:—

An uncoupling mechanism comprising an uncoupling rod pivotally mounted intermediate its extremities and operatively engaging a coupler pin, said rod being provided with an aperture adjacent one extremity, an operating rod comprising angularly disposed arms, one of said arms being pivotally mounted, the other of said arms providing an operating handle, said rod being provided with an aperture adjacent the intersection of said arms, said aperture loosely engaging the aperture of said uncoupling rod, one of said apertures being enlarged to permit free pivotal movement of said uncoupling and operating rods. 40 45

In testimony whereof, I have subscribed my name.

GEORGE C. MURRAY.
